UNITED STATES PATENT OFFICE

1,927,954

BOX TOE CONDITIONING MACHINE

August R. Schoenky, Beverly, Mass., assignor to
United Shoe Machinery Corporation, Paterson,
N. J., a corporation of New Jersey

Application July 31, 1931. Serial No. 554,267

9 Claims. (Cl. 91—46)

This invention relates to a machine for conditioning or tempering articles and is herein illustrated as embodied in a machine of the general type disclosed in United States Letters Patent No. 1,895,574, granted January 31, 1933, on my application, for conditioning stiffening members of shoes, such as box-toe blanks, counters and the like.

Such articles commonly consist of a fabric base impregnated with a stiffening substance, such as celluloid, which may be rendered limp and pliable by treatment with a softening liquid such, for example, as acetone. The blank thus rendered temporarily limp and pliable may be assembled with a shoe upper and an insole upon a last and is subjected first to the operation of a pulling-over machine and then to that of a lasting machine, which operations stretch and pull the upper about the last and secure it in position, the box-toe blank thus being conformed to the toe portion of the last. After the softening liquid has evaporated the box toe becomes stiff and resilient.

The object of the present invention is to produce an improved machine of the type disclosed in my copending application above mentioned.

In accordance with a feature of the invention, two rolls are provided for advancing the work piece, one of the rolls being partially immersed in a liquid in a receptacle and the other roll being outside of the receptacle, means being provided for transferring the work piece from the roll within the receptacle to the roll outside of the receptacle, and a member also being provided for stripping the conditioned work piece from the roll which is outside of the receptacle.

In accordance with another feature a member is provided for stripping the work piece from a conveyor, the stripper member being constructed and arranged to engage the under surface of the work piece as the work piece is advanced by the conveyor and the stripper member being mounted upon a pivotal support which enables the stripper member to tilt away from the conveyor under the weight of the advancing work piece, thereby raising the trailing end of the work piece from the conveyor and avoiding any danger of the conveyor in its movement fraying the trailing end of the work piece.

The invention further consists in various features of construction and combinations and arrangements of parts herein shown and claimed the advantages of which will be apparent to those skilled in the art from the following description,

reference being had to the accompanying drawings, in which

Fig. 1 is a perspective view of a machine embodying the invention;

Fig. 2 is an elevational view in longitudinal section of the machine shown in Fig. 1;

Fig. 3 is a perspective view, showing in detail a member for wiping surplus liquid from a work piece; and

Figs. 4 and 5 are views in longitudinal elevation, showing in detail an instrumentality for stripping the blank from a conveyor.

The frame of the machine consists of a base plate 10 upon which are mounted a pair of side walls 12 connected by a rear wall 14 and by a front wall 16. The space between the above-mentioned walls is divided into a forward compartment and a rear compartment by a partition consisting of an upper member 18 and a lower member 20. The rear compartment is open at the top and its upper portion is occupied by a tank or reservoir 22 for holding a supply of softening liquid to be used in softening work pieces. The reservoir 22 is provided with a handle 24 whereby it may readily be removed from or replaced in the machine.

The work-advancing and work-treating instrumentalities are located within the forward compartment. The softening liquid is contained in a pan 26 disposed in the forward compartment and communicating through a covered passageway 28 with a pan 30 disposed in the rear compartment. In the illustrated machine the pans 26 and 30 and the connecting member in which is formed the passageway 28 are conveniently integral, and the upper partition member 18 is suitably notched to accommodate the connecting member. The reservoir 22 has a feed nozzle 32 which extends downwardly into the rear pan 30 to maintain automatically a constant level of liquid therein determined by the height of the openings of the nozzle 32 above the floor of the pan 30, this arrangement being commonly known as a barometric feed device. Liquid is thus supplied from the reservoir 22 to the forward pan 26 as required. The partition which comprises the members 18 and 20 functions to protect the reservoir 22 from any danger of fire in case the liquid or vapor in the forward portion of the machine should become ignited. The liquid-containing member which comprises the pans 26 and 30 and the passageway 28 is supported upon a pair of rods 34 with provision for adjustment forwardly or rearwardly of the machine for a purpose hereinafter to be explained.

This adjustment is effected by means of a rod 36 which is eccentrically supported by bearings 38 journaled in the side walls 12, one of the bearings being provided with a knurled head (not shown) extending outside of the machine whereby it may be rotated by the operator. The rod 36 passes through a vertical slot formed in a portion 40 of the cover for the passageway 28. The portion 40 extends below the surface of the liquid in the passageway so as to maintain a liquid seal between the forward and rear pans respectively of the receptacle so as to prevent the passage of a flash if the vapor in the forward pan should become ignited.

Extending across the forward compartment of the machine and journaled in bearings formed in the side walls 12 is a shaft 42 carrying a feed roll or carrier 44 having pointed projections formed upon its periphery. The roll 44 is built up longitudinally of circular saw blades and spacing members arranged alternately. The teeth of the saw blades constitute the above-mentioned pointed projections, and the spacing members are of smaller diameter than the saw blades so as to form grooves between the saw blades. The spacing members, in the illustrated machine, have smooth circular peripheries which provide smooth bottoms for the grooves between the saw blades. Both the saw blades and the spacing members are annular in form, having relatively large central openings to enable them to be mounted upon a sleeve 45 of relatively large diameter. The sleeve 45 is provided at each end with an internal flange which fits around the shaft 42. At one end the sleeve 45 is provided with an external flange, the opposite end of the sleeve 45 being externally threaded to accommodate a nut which exerts a clamping pressure through the saw blades and spacing members against the external flange of the sleeve 45. An advantage of the annular form of the saw blades and of the spacing members resides in the fact that the saw blades and spacing members engage each other over relatively small areas. They have less tendency to spring apart, and require less clamping pressure to hold them tightly together, than would be the case if the engaging areas were greater. The roll 44 is partially immersed in the liquid contained in the forward pan 26.

Cooperating with the roll 44 and positioned rearwardly and above the latter is a presser roll 46 which, in the illustrated machine, is of metal and which is carried upon a shaft 48 journaled in a yoke-shaped frame 50. The roll 46 is urged toward the feed roll 44 by means of springs 52 interposed between abutments 54 and the yoke portion of the frame 50. The frame 50 is mounted for pivotal movement upon a rod 58 the ends of which are supported respectively in arms formed on a plate 60 which constitutes a cover plate for the portion of the forward compartment which contains the presser roll 46. An adjusting screw 56 threaded through the cover 60 is provided for varying the pressure of each of the springs 52. If the pressure of the springs 52 is increased sufficiently, the saw teeth of the feed roll 44 will penetrate the work piece to a depth depending upon the amount of the pressure. The roll 44 will thus function as a pricker roll to render the work piece more porous. For those types of work piece, however, which are already sufficiently porous, the pressure of the springs 52 may be relatively weak, in which case the roll 44 functions merely as a feed roll to advance the

work piece by the frictional contact of the saw teeth. The forward portion of the cover plate 60 extends both upwardly and downwardly in the form of a wall 61, the major portion of which is vertical and the lower portion of which curves rearwardly. A stop screw 62 threaded through the wall 61 of the cover plate 60 engages the yoke of the frame 50 and thereby limits the approach of the presser roll 46 toward the feed roll 44.

Extending across the machine over the greater portion of the feed roll 44 is a bracket 64 having a portion 66 which extends downwardly and rearwardly and another portion 68 which extends downwardly and forwardly, the bracket 64 being provided with end flanges through which extend cross bars 70 which are mounted in the side walls 12, the cross bars 70 serving thus to support the bracket 64. The downwardly and rearwardly extending portion 66 of the wall 64 is directed toward the bite of the rolls 46 and 44, and it serves as a guide for feeding work pieces through the machine. The lower and rearwardly curving portion of the wall 61, previously mentioned, assists in directing the work pieces to the bite of the rolls, and together with the wall 66 it constitutes a feed chute. A gate 72 normally closes the opening of the feed chute in order to prevent small articles, and particularly tacks, from being accidentally thrown into the feed chute. The conditioning machine is usually operated in close proximity to a pulling-over machine, which frequently ejects tacks in the course of its operation. The operator occasionally scatters tacks in removing them from the last of an imperfectly pulled-over shoe before presenting the shoe again to the pulling-over machine. If any of the tacks ejected by the pulling-over machine or scattered by the operator should find their way into the interior of the conditioning machine, serious damage would probably be done to the mechanism of the conditioning machine. Furthermore, the resulting sparks would be likely to cause ignition of the vapor within the housing. The gate 72 consists of a flat plate which, at its upper side portions, is provided with lugs which engage notches 74 provided in a pair of side walls 76. This form of mounting the gate 72 enables it to pivot about the above-mentioned lugs and to swing back as the work piece is thrust against it. The side walls 76 extend forwardly from the vertical wall 61, being integral with the vertical wall 61 and the cover plate 60. A cover plate 77 is mounted on the upper edges of the side walls 76 and the vertical wall 61, extending forwardly of the upper edge of the gate 72. Extending crosswise of the machine and carried in the lower forward portion of the bracket 64 is a pair of rods 78 upon which are mounted a plurality of stripper fingers 80 which extend into grooves between the saw blades of the feed roll 44.

The partition member 18 is provided with a forwardly extending flange 82 upon which is mounted one arm of a U-shaped spring plate 84, the other arm being curved about a portion of the feed roll 44. A plurality of spring fingers 86 extending into the pan 26 and around the lower portion of the feed roll 44 are also secured upon the flange 82. A rod 88 extends across the forward portion of the pan 26 and affords a pivotal mounting for a wiper plate 90 which is urged by a spring (not shown) toward the feed roll 44. At each end of the wiper plate 90 is a shoe 92.

which bears against a flange (not shown) on the feed roll 44, thus limiting the approach of the wiper plate toward the roll and preventing the edge of the wiper plate from riding on the points of the roll. Extending upwardly and forwardly from the wiper 90 is a guide plate 94. The provision for forward or rearward adjustment of the pan 26 by means of the rod 36 and eccentrics 38 enables the pressure of the wiper plate 90 toward the roll to be adjusted.

Disposed forwardly of the feed roll 44 and at a level somewhat lower than that of the shaft 42 is a shaft 96 extending across the machine and having its ends journaled respectively in flanges on the forward end plate 16. Mounted upon the shaft 96 is a delivery roll 98 which is similar to the feed roll 44, being composed of circular saw blades and spacer members alternately arranged upon a sleeve 99. In Figs. 4 and 5 the periphery 201 of one of the spacer members is indicated at 201. Extending across the machine above the delivery roll 98 and mounted in flanges on the forward end plate 16 is a bracket 100 having vertically extending guideways 101 formed therein for a member 102 having a curved under surface 104 which serves to remove surplus liquid from the surface of a work piece engaged by the delivery roll 98. At each end of the member 102 is an upstanding lug 103 which slides within its respective guideway 101. A gib 105 is secured to each end of the bracket 100 to retain its respective lug 103 within the guideway 101. The bracket 100 is provided with a lug 106 against which bears a stop screw 108 which is threaded through a rearwardly extending lug 110 formed on the member 102 for limiting the approach of the surface 104 toward the delivery roll 98. The screw 108 is intended for factory adjustment to limit the extreme downward movement of the member 102. A second adjusting screw 112 also threaded through the lug 110 and bearing against the lug 106 is provided for taking care of the more frequent adjustments of the downward movement of the member 102 to accommodate work pieces of varying thickness. A lock-spring 113 surrounding the stem of the adjusting screw 112 prevents the latter from jarring loose. The member 102 is at all times urged downwardly by means of a pair of springs 114 which are interposed between plugs 116 adjustably threaded into the bracket 100 and lugs 118 formed on the member 102. Mounted on the bracket 100 is a tray or shelf 120 for carrying a supply of work pieces.

Extending across the machine forwardly of the delivery roll 98 and somewhat above the level of the shaft 96 is a rod 122 supported by the forward end plate 16. Mounted upon the rod 122 are a plurality of stripper fingers 124 the rear end portions of which extend into grooves of the delivery roll 98. The stripper fingers 124 also have forwardly extending portions 126 which function as a grid to support the work piece after treatment and after delivery by the delivery roll 98. The stripper fingers 124 are pivotally mounted upon the rod 122 and have under surfaces 128 which cooperate with an upper surface 130 of the forward end plate 16 to provide for a limited tilting movement of the stripper fingers 124. A plurality of other stripper fingers 132 are also mounted upon the rod 122. The stripper fingers 132 extend into the grooves of the delivery roll 98 but no provision is made for tilting movement of the fingers 132, these fingers being notched to engage the upper surface 130 and also the inner surface of the end plate 16 in

order to hold the fingers 132 securely in position. The fingers 132 are not provided with any forward extensions. A plurality of members 134 are also mounted upon the rod 122 and are notched about the upper surface 130 and the inner surface of the end wall 16, the members 134 extending into such grooves of the delivery roll 98 as are not occupied by the fingers 124 and 132. The purpose of the members 134 is to gather lint which might accumulate upon the points of the delivery roll 98. The stripper fingers 124 are not distributed uniformly along the length of the rod 122 but are omitted at the central portion of this rod in order to facilitate the grasping of the delivered work piece by the operator. The stripper fingers 124 and 132, and the members 134 are all freely movable lengthwise along the rod 122 to enable them to space themselves as determined by the grooves of the roll 98 with which they register.

The conveying mechanism comprising the rolls 44 and 98 is driven by power supplied to a pulley 136 upon a shaft 138 which is journaled in a bracket 140 secured to the rear wall 14. A shaft 142 is driven from the shaft 138 through reduction gearing 144. The shaft 142 drives a shaft 146 through a clutch 148 having an actuating rod 150 which terminates in a handle 152. The shaft 146 through bevel gearing 154 drives the feed roll 44. Adjacent to the opposite end of the shaft 142 of the feed roll is a gear wheel 156 which through intermediate gearing 158 drives the delivery roll 98. It will be noted that the feed roll 44 and the delivery roll 98 are driven in opposite directions, the former counterclockwise and the latter in a clockwise direction, as viewed in Fig. 2. The teeth of the saw blades which constitute the pointed projections of the feed roll are inclined toward the direction of rotation in order to enable them more effectively to advance the dry work piece by frictional engagement. The projections 115 of the delivery roll 98, however, are inclined away from the direction of rotation in order to prevent them from gouging into the now softened work piece and to avoid any danger of fraying the trailing end of the work piece after the latter has been 120 delivered upon the stripper fingers 124.

A drip pan 160 is provided in the lower portion of the rear compartment of the machine, and a drip pan 162 is provided in the lower portion of the forward compartment. The reservoir 22 is so 125 shaped as to avoid interference with the power-transmission system.

In operation, the work pieces are taken up one by one from a stack resting on a shelf 120 and are inserted through the chute formed between the inclined plate 66 and the lower curved portion of the wall 61. The swinging plate 72 readily yields to permit entry of the work piece. The leading edge of the work piece is pressed against the teeth of the feed roll 44 by the presser roll 46. The springs 52 may be tightened by the adjusting screws 56 to cause more or less penetration of the work piece, if greater porosity of the work piece is desirable to enable it to take up conditioning liquid more readily. If the work piece is already sufficiently porous, the pressure of the springs 52 may be adjusted merely to cause frictional driving engagement between the roll teeth and the work piece without penetration. The spring plate 84 and the spring fingers 86 serve to 130 maintain the work piece in engagement with the feed roll 44 in case the work piece is not impaled upon the saw teeth. As the work piece is carried up out of the liquid in the pan 26, the surplus liquid is wiped from it by the wiper plate 90, and 135

- it is stripped from the feed roll 44 by the stripper fingers 80. The under surfaces of the stripper fingers, together with the upwardly and forwardly extending guide member 94 which is carried upon the wiper 90, directs the work piece to the delivery roll 98. The leading end of the work piece is advanced by the rotation of the delivery roll underneath the curved under surface 104 of the member 102. The surface 104 is so shaped that at the locality of approach of the work piece it is spaced a relatively greater distance from the delivery roll to avoid contact with the approaching work piece, the work-engaging surface gradually approaching the roll in the direction of advance of the work piece so that the work piece enters gradually into contact with the under surface of the member 102 and enables this surface to remove surplus liquid from the work piece without scraping any softened solid material from the surface of the work piece. The member 102 serves also to maintain the work piece in feeding engagement with the delivery roll, and it may, if desired, be utilized, by adjustment of the stop screw 112 and of the spring abutments 116, to press the work piece against the teeth of the delivery roll with sufficient force to effect partial penetration. In that case some of the conditioning liquid which adheres in the form of a very thin film to the work piece and to the teeth of the delivery roll will be introduced into the interior of the work piece. As the work piece is further advanced by the delivery roll, the stripper fingers 124 engage the under surface of the work piece and as the work piece advances forward beyond the supporting rod 122 the stripper fingers tilt so as to raise the trailing end of the work piece away from the delivery roll so that the trailing edge of the work piece is out of contact with the pointed projections.
- Having thus described my invention, what I claim as new and desire to secure by Letters Patent of the United States is:—
1. A conditioning machine having, in combination, means for subjecting a work piece to the action of a softening medium and a driven roll constructed and arranged to deliver the treated work piece from said subjecting means, said delivery roll having a plurality of pointed work-engaging projections inclined away from the direction of rotation of said delivery roll to avoid damaging the softened work piece.
  2. A conditioning machine having, in combination, means for subjecting a work piece to the action of a softening liquid, a driven roll constructed and arranged to deliver the treated work piece from said subjecting means, said delivery roll having a plurality of pointed work-engaging projections inclined away from the direction of rotation of said delivery roll to avoid damaging the softened work piece, and a member constructed and arranged to press against the work piece as the work piece is advanced by said delivery roll to remove surplus softening liquid which may adhere to the work piece.
  3. A conditioning machine having, in combination, a receptacle for a conditioning liquid, a driven feed roll partially immersed in the liquid in said receptacle, said feed roll having a plurality of work-engaging projections inclined in the direction in which said feed roll is driven, means for holding a work piece against said roll whereby said roll in its rotation carries the work piece through the liquid in said receptacle, a driven delivery roll outside of said receptacle, means for transferring the work piece from the feed roll to the delivery roll.
  4. A conditioning machine having, in combination, a receptacle for a conditioning liquid, a driven roll partially immersed in the liquid in said receptacle, a plurality of spring fingers curved about that portion of the roll which is immersed in the liquid for holding a work piece against the roll in driving engagement therewith, a driven roll outside of the receptacle, means for transferring the work piece from the first-mentioned roll to the second-mentioned roll, and a member constructed and arranged to strip the work piece from the periphery of the second-mentioned roll.
  5. A conditioning machine having, in combination, a driven roll having pointed projections for engaging one side of a work piece to advance the work piece, means for subjecting the work piece advanced by said roll to the action of a conditioning medium, a second roll having pointed projections for advancing the work piece, and means for transferring the work piece from the first-mentioned roll to the second-mentioned roll with the opposite side of the work piece in engagement with the second-mentioned roll, the projections of the first-mentioned roll being inclined toward the direction of rotation to enable them effectively to advance the dry work piece by frictional engagement therewith, and the projections of the second-mentioned roll being inclined away from the direction of rotation to avoid gouging the surface of the softened work piece.
  6. In a conditioning machine, means for subjecting a work piece to the action of a conditioning liquid, a roll for advancing the work piece after the work piece has been subjected to the action of the conditioning liquid, and a member constructed and arranged to press against the work piece as the work piece is advanced by said roll to remove surplus conditioning liquid which may adhere to the work piece, said member having a smooth concave work-engaging surface which at the locality of approach of the work piece is spaced a relatively greater distance from the roll than the major portion of the work-engaging surface to avoid contact with the approaching work piece, said work-engaging surface gradually approaching the roll in the direction of advance of the work piece, whereby the work piece enters gradually into contact with the surface of said member and enables said member to remove surplus liquid without scraping any softened solid material from the surface of the work piece.
  7. In a conditioning machine, a conveyor for a work piece, a stripper constructed and arranged to engage the under surface of the work piece as the work piece is advanced by said conveyor, thereby stripping the work piece from said conveyor, and a pivotal support for said stripper constructed and arranged to enable said stripper to tilt away from said conveyor under the weight of the advancing work piece.
  8. A conditioning machine having, in combination, mechanism for conditioning a work piece, a feed chute constructed and arranged to direct the work piece to said conditioning mechanism, and a gate closing the entrance to said feed chute to prevent the accidental introduction of undesirable objects such as tacks to said conditioning mechanism, said gate being pivotally suspended for free swinging movement to enable it to be opened by the insertion of a work piece.

9. A machine for treating shoe stiffeners made of fabric impregnated with a stiffening substitute having, in combination, a receptacle for liquid, a member for receiving the stiffeners and immersing them in the liquid, a downwardly extending chute having its delivery end adjacent to said immersing member, a substantially horizontal, stiffener-supporting plate terminating at

its rear edge adjacent to the mouth of the chute, and a normally vertical gate in the form of a thin plate suspended for free swinging movement about a horizontal axis located above the supporting plate in position to close the mouth of the chute. 80

CERTIFICATE OF CORRECTION.

Patent No. 1,927,954.

September 26, 1933.

AUGUST R. SCHOENKY.

It is hereby certified that error appears in the printed specification of the above numbered patent requiring correction as follows: Page 4, after line 75, claim 3, insert the words said delivery roll having a plurality of work-engaging projections inclined away from the direction in which the delivery roll is driven to avoid damaging the softened work piece, and; and that the said Letters Patent should be read with this correction therein that the same may conform to the record of the case in the Patent Office.

Signed and sealed this 21st day of November, A. D. 1933.

F. M. Hopkins

(Seal)

Acting Commissioner of Patents.
